Assignment

Des 1640

The Lowell Manufacturing Company.
Letters Patent No. 1640, dated Aug. 12, 1862.

The schedule referred to in these Letters Patent and making part of the same,
— — — — —

To all whom it may concern:

Be it known that I, Clemir J. Ney, of Lowell,
in the County of Middlesex and State of Massachusetts, have originated
and designed a new Pattern for Carpets or other fabrics, of which the
following is a full, clear and exact description, reference being had
to the accompanying drawings, making part of this specification.

This pattern consists chiefly of series of figures, com-
posed of scrolls, lines and blocks. Lining between the figures are
small solid lines which are continued in dotted lines, which by their
connections divide the design into large diamonds. The remainder of
the design is occupied by two kinds of ground work, the one dotted, the
other composed of small blocks.

The colors employed for the different portions of the de-
sign, may be varied to suit the taste and wish of the manufacturer.

Claim —

What I claim as my invention and desire to secure
by Letters Patent, is the design or pattern for Carpets or other fabrics, herein
set forth.
